RAILROAD GRADE CROSSING SIGNAL

Edward R. Anderson, Van Horn, Tex.

Application August 25, 1938, Serial No. 226,827

5 Claims. (Cl. 246—126)

This invention relates to safety devices for railroad grade crossings and more particularly to a new and improved grade crossing safety device actuatable by approaching trains and including a plurality of flags positioned in portions of the grade crossing and adapted to being moved transversely across the line of traffic.

It is one of the more important objects of the present invention to provide a new and improved grade crossing signaling means which although comprising relatively few parts, is nevertheless rugged in structure and dependable in service and which is actuatable by railroad trains for indicating approach of said trains toward the grade crossing.

Another object of the present invention is to provide a simple but dependable grade crossing signaling means of the type referred to including a plurality of pendulum actuated flags, positioned within housings located adjacent the grade intersection, said flags being actuatable by a train approaching said crossing.

Another object of the present invention is to provide a grade crossing signaling device of the type referred to, characterized by including means for retracting the signaling flags thereof within the housing subsequent to passage of the train beyond the grade intersection.

One of the important advantages of the novel signaling device according to the present invention, is that it is actuated, in a major part at least, by gravity and accordingly does not necessitate expensive electrical or pneumatic equipment for its operation, which would necessitate increasing initial costs as well as cost of up-keep.

Another advantage in the novel grade crossing signaling device according to the present invention, is that the elements thereof are of relatively simple but rugged construction, thereby suiting the device to the requirements of mass production, with accompanying economies of manufacture.

Among the more important features of the novel signaling device according to the instant invention are its dependability during use resultant from its simplicity of construction and arrangement of structural elements, whereby jamming of the mechanism is at least largely precluded; its adaptability for use with signaling flags of various types, particularly those formed of relatively flexible material, such as sheet rubber or the like; and its efficacy as a grade signaling device, that is to say, its inherent advantageousness resultant from location of the device

directly in the line of vision of persons crossing the grade intersection.

Other objects, advantages and features of the device according to the present invention will be apparent to those skilled in the art during the course of the following description.

Regarded in certain of its broader aspects, the present invention comprises a freely rotatable shaft mounted beneath a railroad road-bed at a grade intersection, flags carried on ends of said shaft, a pendulum associated with said shaft for, upon occasion, imparting swinging motion or rotation in alternate directions thereto, a housing for said flags, means for holding said flags within said housings and said pendulum in other than equilibrium position, means actuatable by a train approaching said grade crossing for causing release of said flags, whereby said pendulum causes said flags to move from within said housing to a position exterior thereof with reciprocation of the flags while exposed, and means actuatable by passage of said train over said crossing whereby said flags are returned within said housings and retained therein subject to subsequent operation as aforesaid.

In order to facilitate a fuller and more complete understanding of the present invention, a specific embodiment thereof will be hereinafter described, it being clearly understood, however, that the illustrated embodiment is given solely by way of example and is non-limitative upon the scope of the present invention except as expressed in the subjoined claims.

Referring then to the drawings:

Figure 1 is substantially a top plan view of a railroad grade intersection showing the novel signaling means according to the present invention in position of use, together with switch controlling means therefor, parts being broken away for clearness of illustration.

Figure 2 is substantially a vertical sectional view of Figure 1, taken along the line 2—2 thereof, with the signals or flags shown in raised position.

Figure 3 is substantially a vertical sectional view of Figure 2 with the signal shown in retracted position within the housing.

Figure 4 is a vertical sectional view of Figure 2, taken along the line 3—3 thereof, showing the signal in extended position.

Figure 5 is a fragmentary detail sectional view illustrating a portion of the shaft bearing, and

Figure 6 is essentially a schematic circuit diagram of the presently preferred embodiment of the instant invention.

Referring now especially to Figures 1 and 2, a grade crossing generally designated by the numeral 10, comprising a traffic lane 11, and railroad tracks 12, intersecting said traffic lane, 5 is provided at the place of intersection with signaling means, generally designated by the numeral 13. The signaling means 13 comprises a shaft 14, extending transversely beneath said railroad tracks 12, positioned within a hollow 10 substantially tubular casing member 15 and essentially freely rotatably mounted in bearings 16 and 17 mounted on walls of casings 18 and 19, respectively. The casings 18 and 19 are essentially box-like and are provided with openings 20 and 21 formed in the top sides thereof and extending longitudinally along said casing tops substantially perpendicular to the axis of rotation of the shaft 14.

Signaling flags 22 and 23, to be hereinafter 20 described, are fixedly mounted, by means including collars 24 and 25, upon end portions of the shaft 15, whereby said flags, upon occasion, can be moved through the slot-like openings 20 and 25 in the casings 18 and 19 and disposed in position essentially perpendicular to the surface of the traffic lane 11.

Referring now especially to Figures 2 and 3, it 30 will be noted that the flag 23 comprises an essentially rectangular paddle-like member, generally designated by the numeral 30 mounted at a place intermediate the length but near an end thereof, on the shaft 14 by means including a collar 25 substantially as hereinbefore described. A notch 31 is formed in the distal free 35 end of said member 30, substantially as shown in Figure 4. The end of the flag 23 nearest the shaft 14 carries a weight 32 essentially fixedly attached thereto and adapted to act, under the influence of gravity and momentum, as a pendulum, whereby said flag, upon occasion, can be moved into essentially vertical position and rocked into other positions substantially as shown in phantom in Figure 4.

It is to be understood that the flag 22 is substantially the same as the flag 23, being provided with a weighted end portion 33 similar to and functioning in an analogous manner to the weighted end portion 32 of the flag 23, and that the flags 22 and 23 are disposed in a common plane together with the shaft 14. It is to be noted however, that the flag 22 is not provided with a notch in the free end thereof as is the flag 32 hereinbefore described.

In the presently preferred embodiment of the 55 instant invention, essentially free rotation of the shaft 14 is facilitated by the bearings 16 and 17, one of which is illustrated in Figure 5 and each of which comprises a U-shaped trough-like member adapted to receive the end portion of the shaft 14 when positioned therein, substantially as shown.

The novel flag retention means for holding the flags within the housing and the pendulum in position other than equilibrium position, will 60 now be described, reference being had particularly to Figures 3 and 4. A first-class lever 43, pivotally mounted and fulcrumed on the standard 41 attached to a wall of the casing 19, is pivotally connected to the cross member 42, attached to a third-class lever 43 pivotally mounted on the standard 44 attached to the bottom of the casing 19 substantially as shown. A resilient spring-like member 45 attached to a casing wall and to the member 43 normally presses the member 43 against the stop 46 and the member 40

against the stop 47, whereby said members 40 and 43 are disposed in essentially vertical position. Projecting latch elements 48 and 49, mounted in the distal end portions of the members 40 and 43 respectively, are adapted to engage with the notch 31 formed in the distal end portion of the flag 23, when said flag is disposed in horizontal position whereby, through engagement of one of said latch elements with said notch, said flag can be retained in essentially horizontal position whereby it is substantially completely within the casing 19 and the weight 32 is in a non-equilibrium position. It will be understood of course, that when the flag 23 is retracted within the casing 19, the flag 22 is retracted within the casing 48.

When the device is in use, the flags are normally in retracted position within the casing: the manner in which the latch elements are disengaged from the flags whereby the pendulums 20 are permitted to move said flags into essentially vertical position will now be described. A vertically positioned third-class lever member 50, pivotally mounted in the standard 51 attached to the casing 19, is connected to an end portion 25 of the member 40 whereby movement of said member 50 can result in movement of the member 43, with concomitant movement of the member 48, whereby the latch elements 48 and 49 are disengaged from end portions of the flag, the 30 positions of the various levers being shown in phantom in Figure 4.

It will be noted that although the member 50 is directly connected only to the member 40, nevertheless, a flag engaged with either of the 35 latch elements 48 or 49 would be disengaged therefrom by clockwise movement of said member 50 about its pivot point. Accordingly, the flag can be disengaged and permitted to move from either one of its positions of rest. The release lever 50 is actuated by means including a relatively stationary solenoid 52 acting upon a keeper 53 mounted on the lever member 50 whereby current passing through said solenoid causes clockwise rotative movement of the member 50 about its pivotal point thereby releasing the flag 23 as aforesaid. The solenoid 52 is controlled by a train approaching the grade intersection, as will be hereinafter described.

The means for moving the flags into retracted 50 position within the housings and engaging same with the latch elements hereinbefore referred to, will now be described, reference being made particularly to Figures 3 and 4. Relatively stationary solenoids 55 and 56 mounted within the casing 19 and having cores 57 and 58 respectively, are connected by means of cables 59 and 60 with the end portion of the shaft 14 substantially as shown. The cables 59 and 60 normally hang freely and do not interfere with rocking motion of the shaft 14, the cables being held in guide members 61 and 62 mounted within the casing, and the cores 57 and 58 are normally pressed outwardly relative to the solenoids by springs 63 and 64 respectively. When current is passed through one of the solenoids 55 or 56, it will be evident that the core 57 or 58, as the case may be, will be drawn within the solenoid thereby tensioning the cable 59 or 60 and exerting torque action upon the shaft 14, whereby the flags are moved 65 into retracted position within the housing and the notched end portion 31 of the flag 23 engaged with one of the latch elements 48 or 49. It will be noted that current passing through the solenoid 55 will cause engagement with the flag end por- 70

tion with the latch element 49: current passing through the solenoid 56 will cause engagement of the flag end portion with the latch element 48.

The manner in which current is supplied to the solenoids 52, 55 and 56 whereby the device is operated and controlled, will now be described, reference being made particularly to Figure 6 of the drawings.

It is to be understood that railroad vehicles traveling on the railroad line crossing the intersection are provided with a suitable switch actuating means extending from the left side thereof and adapted to actuate co-operating electrical switch members disposed adjacent left-hand portions of the railroad road bed. Switches 70 and 71, positioned adjacent left-hand portions of the railroad road bed generally designated by the numeral 72, are each connected in series with the solenoid 52 and a power source, such as batteries or the like, 73. It will be noted that the switches 70 and 71 are positioned on opposite sides of the road bed and accordingly, irrespective of which direction vehicles travel over the railroad bed, one of the switches 70 or 71 will be positioned on the left-hand side of the bed and in a location precedent to the intersection. In the preferred embodiment of the present invention, the distance between the railroad intersection and the switch is adjusted whereby adequate warning of the approaching trains is given to persons traversing the intersection. The solenoids 55 and 56, which function to return the signaling means to rest position, are actuated by the switches 75 and 76 respectively, with which they are connected in series to the power source 73 substantially as shown in the schematic circuit diagram, Figure 6. The switches 75 and 76 are preferably positioned at the intersection or slightly beyond same, whereby the signaling means are not returned to rest position until the train or the like has passed the intersection.

It will be noted that referring now to Figure 6, assuming a train is passing from left to right along the road bed 72, the switch 70 will be actuated as the train approaches the intersection thereby releasing the flags and permitting same to rise and rock in the field of vision of persons traversing the intersection whereby said persons will be notified of the train's approach. When the train passes the intersection, the switch 75 will be actuated thereby causing current to pass through the solenoid 55, whereby the notched end portion 21 of the flag 23 is caused to engage with the latch elements 49. Similarly, assuming a train is moving on the road bed 72 from right toward the left thereof as illustrated in Figure 6, the switch 71 would be actuated prior to the train's arrival at the intersection and subsequently thereto, the switch 76 would be actuated whereby current passing into the solenoid 56 would move the flags into retracted position of rest.

It will be evident that current flows through the solenoids 52, 55 and 56 only when the device is in actual use. Accordingly, the current drained from the power source 73 is relatively small, thereby resulting in economy of operation.

From the foregoing it will be apparent that a train approaching the intersection irrespective of its direction of travel will actuate either the switch 70 or 71 whereby the latch elements 48 or 49, as the case may be, will be disengaged from the signal flag 30 thereby permitting said signal flag to move into essentially vertical position by action of gravity upon the weighted end portion 32. Inasmuch as the flag is pivoted and

the end portion 32 is weighted, the latter in effect becomes a pendulum and through forces including momentum and gravity, the exposed flag is waved or oscillated. When the train passes the intersection, one of the switches 75 or 76 is actuated whereby current is transmitted to one of the solenoids 55 or 56 as the case may be, thereby exerting a pull upon the connecting lines 59, causing rotation of a shaft 14 with resultant movement of the signal flag into concealed position and engagement of a latch element with one of the flags as hereinabove described.

In the presently preferred embodiment of the instant invention, the flags 22 and 23 are made of relatively flexible but resilient material, such as heavy sheet rubber or the like, whereby a vehicle accidentally striking against extended flags will not damage same.

It is to be understood that this improvement is capable of extended application and is not confined to the exact showing of the drawings nor to the precise construction described and, therefore, such changes and modifications may be made therein as do not affect the spirit of the invention nor exceed the scope thereof as expressed in the appended claims.

What is claimed as new is:

1. A railroad grade-crossing signaling device of the type described comprising a casing positioned beneath and extending transversely relative to the railroad bed at the grade-crossing; a shaft, freely rotatably mounted within said casing; paddle-shaped signal flags mounted on said shaft and rotatable therewith; housings for at least largely concealing said flags except when in essentially vertical position; gravity and momentum controlled means for alternately rotating said shaft in opposite directions and swinging said signal flags while exposed; means comprising latch elements for holding said flags in concealed positions within said housings; means actuated by a train approaching said grade-crossing for releasing said flags from engagement with said latch elements, and means actuated by passage of a train over said grade-crossing for returning said flags to substantially horizontal position within said housing and engaging same with said latch elements.

2. A railroad grade-crossing signaling device of the type described comprising a casing positioned beneath and extending transversely relative to the railroad bed at the grade-crossing; a shaft, freely rotatably mounted within said casing; paddle-shaped signal flags mounted on said shaft and rotatable therewith; housings for at least largely concealing said flags when in essentially horizontal position but exposing same when in other positions; gravity and momentum controlled means for alternately rotating said shaft in opposite directions and swinging said signal flags while exposed; said means comprising a pendulum mounted on said shaft and having a rest position corresponding to essentially vertical position of said flags; means for holding said flags in concealed positions within said housings; said means comprising spring pressed latch elements engaging, upon occasion, with part of said flags; means actuated by a train approaching said grade-crossing for releasing said flags from engagement with said latch elements, and means actuated by passage of a train over said grade-crossing for returning said flags to substantially horizontal position within said housing and engaging same with said latch elements.

3. A railroad grade-crossing signaling device

- of the type described comprising a casing positioned beneath and extending transversely relative to the railroad bed at the grade-crossing; a shaft, freely rotatably mounted within said casing; paddle-shaped signal flags mounted on said shaft and rotatable therewith; housings for at least largely concealing said flags when in essentially horizontal position but exposing same when in other positions; gravity and momentum controlled means for alternately rotating said shaft in opposite directions and swinging said signal flags while exposed; means comprising latch elements for holding said flags in concealed positions within said housings; means actuated by a train approaching said grade-crossing for releasing said flags from engagement with said latch elements; said means comprising a switch operable by said train, a power source and a solenoid operably connected by said switch, a magnetically sensitive member and a lever system connected to said latch elements and cooperating with said solenoid whereby operation of said switch causes releasing motion of said latch elements, permitting said gravity and momentum controlled means to move said flags into exposed position and rock same; and means actuated by passage of a train over said grade-crossing for returning said flags to substantially horizontal position within said housing and engaging same with said latch elements.
4. A railroad grade-crossing signaling device of the type described comprising a casing positioned beneath and extending transversely relative to the railroad bed at the grade-crossing; a shaft, freely rotatably mounted within said casing; paddle-shaped signal flags mounted on said shaft and rotatable therewith; housings for at least largely concealing said flags when in essentially horizontal position but exposing same when in other positions; gravity and momentum controlled means for alternately rotating said shaft in opposite directions and swinging said signal flags while exposed, said means comprising a pendulum mounted on said shaft and having a rest position corresponding to essentially vertical position of said flags; means for holding said flags in concealed positions within said housings; said means comprising spring pressed latch elements engaging, upon occasion, with parts of said flags; means actuated by a train approaching said grade-crossing for releasing said flags from engagement with said latch elements, said means comprising a first switch operable by said train, a source of energy and a first solenoid operably connected by said switch, a magnetically sensitive member and a lever system, connected to said latch elements and cooperating with said first solenoid whereby operation of said switch causes releasing motion of said latch elements, permitting said gravity and momentum controlled means to move said flags into exposed position and rock same; and means actuated by passage of a train over said grade crossing for returning said flags to substantially horizontal position within said housing and engaging same with said latch elements, said means comprising a second switch operable by said train, a source of energy, a second solenoid, a spring pressed core for said solenoid normally held adjacent but exterior thereof, and a connector attached to said core and to parts of said shaft whereby operation of said switch causes movement of said core to a position interior of said second solenoid with application of torque force to and rotation of said shaft.
5. A railroad grade-crossing signal comprising a freely rotatably mounted shaft extending transversely relative to and beneath the railroad bed at the grade-crossing; signal flags mounted on said shaft and rotatable therewith; housings for at least largely concealing said flags when in other than essentially vertical position; gravity and momentum controlled means for oscillating said shaft and swinging said flags in exposed position; latches for holding said flags in concealed position within said housings; means actuated by an approaching train for releasing said latches; and means actuated by passage of a train over said grade crossing for returning said flags to concealed position and engaging same with said latch elements.
